TABLE HINGE

Joseph L. Fitzpatrick, San Francisco, Calif.

Application August 5, 1941, Serial No. 405,505

2 Claims. (Cl. 311—52)

This invention relates to improvements in hinge constructions and has particular reference to a hinge used in conjunction with tables of the folding type, whereby the leaves of the table may be quickly brought into operative position to present an even alignment of the table leaves, and when collapsed, there is effected a smooth even corner to thus provide a table that is neat and attractive in appearance when it is in either an open or closed position.

The principal object of the invention is the provision of an intermediate member positioned between and connected to a pair of table leaves through the medium of my improved hinge construction to thus effect a ready assembly of the table to an operative or open position, and wherein the leaves are absolutely flat and in alignment, or, on the other hand, to realize, by a raising of the intermediate member, a compact and neat appearance of the table when the latter is collapsed or folded.

A further object of the invention is the provision of a stop element in conjunction with a hinge, whereby the leaves are retained in a vertical position when the table is collapsed or folded.

An additional object of the invention is the provision of a hinge construction that is economical to manufacture, simple in construction, positive in operation, and highly effective and serviceable in use.

Other objects and advantages will be apparent during the course of the following description.

In the accompanying drawing forming a part of this specification and in which like numerals are employed to designate like parts throughout the same,

Fig. 1 is a side elevational view of a folding table, showing an intermediate member located underneath the folding leaves when the leaves are in their open position and the position of the new and improved hinges with respect to said intermediate member and leaves;

Fig. 2 is an end elevational view of the table, illustrating the position of the hinges when the leaves are in their closed position;

Fig. 3 is a bottom plan view of the table and hinges, and in this particular view the legs are not illustrated;

Fig. 4 is an enlarged side elevational view of the hinge and also showing a portion of a table leaf and the intermediate member in dot-and-dash outline and illustrating the exact position of the hinge when the leaf is in its open position;

Fig. 5 is a side elevational view of the same elements shown in Fig. 4, illustrating the exact

position of the hinge when the leaves are in their closed position; and

Fig. 6 is a view of the hinge shown in Fig. 4, looking in the direction of the arrow A, and illustrates the extension that is provided on the hinge to serve as a stop to hold the table leaf vertically when the latter is in its downward position, as shown in Fig. 5.

In the present invention four hinges are employed, as illustrated to advantage in Fig. 5; but since all the hinges are of similar construction, only one will be described. In the accompanying drawing wherein for the purpose of illustration is shown a preferred embodiment of my invention, it will be noted that the hinge *per se* embodies in its construction a central curved body 7 that has pivotally connected thereto two leaves or flat side members 8 and 9, the medium for effecting the connection comprising pintles 10 and 11, respectively. One end of each of the side members 8 and 9 has a male joint, one of which engages with the female joint formed on each end of the central curved body 7, and the said joints are adapted to receive the pintles 10 and 11, thus forming the hinge, as illustrated in Figs. 4, 5 and 6. The flat portion of the side member 9 is wider than the flat portion of the side member 8 and has a vertical extension or stop 12 that holds the table leaves in a vertical position, as shown in Figs. 2 and 5, when the table leaves are in their downward position. The said extension 12 may be of any desired length.

The numeral 14 indicates an intermediate table leaf that is provided underneath the table leaves 15 and 16 and arranged in the center where the ends of the table leaves 15 and 16 meet when they are in their open position, as shown in Fig. 1.

The table has two standard gates 17 and 18, having suitable legs for supporting the table leaves. The detail of these gates is not shown, as they are of conventional type.

The numerals 20 and 21 designate openings in the side members 8 and 9 respectively to accommodate suitable nails or screws for fastening the side members to the table leaves.

It will be noted that the curved body 7 of the hinge fits over the end of the intermediate leaf 14 when the folding leaf is in its open position, as shown in Figs. 1 and 4, and lies directly underneath said intermediate leaf when the folding leaves are in their closed position, as shown in Figs. 2 and 5. It will be further observed that the relationship between the thickness of the intermediate leaf and the distance between the

two pintles 10 and 11 of the hinge is such as to cause a smooth even corner to be formed when the folding leaf is in its closed position, as shown in Fig. 5.

From the foregoing description, considered in connection with the accompanying drawing, it will be obvious that I have produced a most efficient hinge construction that will have a wide field of use in the furniture industry.

It is to be understood that the form of my invention herewith shown and described is to be taken as a preferred example of the same and that various changes relative to the material, size, shape and arrangement of parts may be resorted to without departing from the spirit of the invention or the scope of the subjoined claims.

Having thus described my invention, I claim:

1. In combination with a pair of table leaves, of an intermediate cross member positioned beneath the inner meeting ends of the table leaves and a hinge effecting a connection between the intermediate cross member and the table leaves, said hinge comprising an end section secured to said intermediate cross member and an end section secured to a leaf section, and a central

portion having pivotal connection with said end sections for effecting a raising and lowering of said intermediate member relative to said table leaves, whereby the bottom surface of the inner portions of said pair of table leaves rests directly onto the top surface of the intermediate cross member when the table leaves are in their open position.

2. In combination with a pair of table leaves, 10 of an intermediate cross member positioned beneath the inner meeting ends of the table leaves and a hinge effecting a connection between the intermediate cross member and the table leaves, 15 said hinge comprising an end section secured to said intermediate cross member and an end section secured to a leaf section, stop means carried by the first-mentioned end section, and a curved central portion having pivotal connection with said end sections for effecting a raising and lowering of said intermediate member relative to said table leaves, whereby the bottom surface of the inner portions of said pair of table leaves rests directly onto the top surface of the intermediate cross member when the table leaves are in their open position.

JOSEPH L. FITZPATRICK.
